UNITED STATES PATENT OFFICE.

OLIVER HOWARD GENTRY, OF ROCHESTER, NEW YORK.

SEWING-MACHINE ATTACHMENT.

1,409,049.

Specification of Letters Patent.

Patented Mar. 7, 1922.

Application filed May 24, 1921. Serial No. 472,041.

To all whom it may concern:

Be it known that I, OLIVER H. GENTRY, a citizen of the United States, and a resident of Rochester, in the county of Monroe and State of New York, have invented a new and Improved Sewing-Machine Attachment, of which the following as a full, clear, and exact description.

This invention relates to sewing machine attachments. Prior to this invention single spring attachments were used to assist the operator but if he did not use proper precaution on stopping they might cause the machine to run backward one or more revolutions which often broke the thread or needle.

The object of this invention is to produce a spring-balance device that may be attached to any sewing machine and so adjusted as to be of assistance to the operator and which eliminates the danger of running the machine backwards when the operator ceases to apply the driving force.

This object is accomplished by providing, in conjunction with the treadle of a sewing machine, a lever-carrying means having a lever at right angles thereto, and means for balancing the lever in a vertical position.

This invention will be more clearly understood from the following detailed description and accompanying drawings.

Figure 1 is a top plan view of the device showing it attached to a sewing machine; and

Figure 2 is a side elevation showing it connected to a sewing machine.

Referring to the above-mentioned figures, a treadle 1 is mounted on the shaft 2 which is carried by the frame 3 of the sewing machine. A metal strip 4, which has a hook member 5 at one end and a supporting stud 6 at the other, has connected to the end which carries the stud a threaded bolt member 7. Clip 8 which has an opening therethrough fits over the bolt member 7 and is held thereon by means of a wing nut 9 which engages with the bolt 7. This metal strip may be connected to the treadle of any sewing machine by fitting the hook member 5 over one side of the treadle 1, and clip 8 over the other, and adjusting the wing nut 9 to clamp it in position. The stud 6 engages with the top of the treadle 1 so as to

eliminate any vibration of the metal strip that might take place during the operation of the treadle.

A metal plate 13 is fixed to the metal strip 4 and extends at right angles thereto. Fixed to the metal plate 13 are headed pins 14 which are arranged in vertical rows. 60 Clamps 10 are fitted on the frame 3 and held in engagement therewith by means of hook-headed bolts 11 and wing nuts 15, which engage with these bolts. The plate 13, which really forms a lever arm, is connected 65 to the clamps 10 mounted on the frame 3 by means of springs 12 which are extended between the hook-headed bolts 11 and the headed pins 14 fixed to the plate 13.

When the treadle 1 is rocked on the shaft 70 2, the lever arm 13 oscillates about the shaft, and the oscillation of the lever arm in one direction extends one of the springs 12 and allows the other to contract. On reaching a limit of oscillation the extended spring 75 tends to draw the lever arm back to its vertical position and thus assists the operator. If the operator at this point removes his foot from the treadle the extended spring 80 will move the lever arm towards its vertical position, and as it moves it will gain sufficient momentum to carry it beyond a vertical position, but any movement beyond a vertical position is retarded by the other spring which will then become extended, and 85 so after the operator ceases to apply force to the treadle the machine will be brought to rest by the springs without making a revolution either backward or forward.

Having thus described my invention, I 90 claim as new and desire to secure by Letters Patent:—

1. In combination with a sewing machine including a frame and treadle, a spring balance device comprising a strip mounted on 95 the treadle, a metal plate fixed to the strip and extending at right angles thereto, and spring means for connecting the plate to each side of the frame.

2. In combination with a sewing machine 100 including a frame and treadle, a spring balance device comprising a strip, adjustable means co-operating with the strip to connect it to the treadle, a lever arm fixed to the metal strip and extending at right angles 105 to it, and spring means connecting the lever

arm to each side of the frame to balance it in a vertical position.

3. In combination with a sewing machine including a frame and treadle, a spring balance device comprising a rigid strip, adjustable means co-operating with the strip to connect it to the treadle, a lever extending at right angles to the strip and fixed to

it, a plurality of headed pins fixed to the lever, a plurality of clamps held in engagement with each side of the frame, and spring means for connecting any of the headed pins to the clamps to balance the lever in a vertical position. 10

OLIVER HOWARD GENTRY
